UNITED STATES PATENT OFFICE.

FRED M. TURCK, OF CHICAGO, ILLINOIS.

STAND FOR TABLETS OR CALENDARS.

SPECIFICATION forming part of Letters Patent No. 433,635, dated August 5, 1890.

Application filed December 16, 1889. Serial No. 333,941. (No model.)

To all whom it may concern:

Be it known that I, FRED M. TURCK, a citizen of the United States, residing at Chicago, in the county of Cook and State of Illinois, 5 have invented a certain new and useful Improvement in Stands for Tablets or Calendars, of which the following is a specification.

The object of my invention is to provide a simple and serviceable construction of tablet 10 or calendar stand or holder which can be made at small cost; also, to provide the stand with means for permitting a book or pack of tablet or calendar leaves to be held open and in a flat condition.

15 To the attainment of the foregoing and other useful ends my invention consists in matters hereinafter set forth, and particularly pointed out in the claims.

In the accompanying drawings, Figure 1 20 represents a blank from which the stand can be formed. Fig. 2 represents in perspective the blank bent to partially form the stand. Fig. 3 shows in perspective the completed stand with a set of memoranda or calendar 25 leaves held thereon. Fig. 4 represents on a larger scale a horizontal section taken through the back of the stand and the leaves thereon at a point to show one of the staples by which the leaves are attached to said back. Fig. 5 30 represents the staple of Fig. 4 prior to bending its ends.

In Fig. 1, A indicates the blank, which can be either of sheet metal or card-board, but preferably the latter. In said figure the dotted lines 1 1 2 3 3 indicate lines along which the blank is to be bent, while the full lines 4 4 denote lines of separation. The blank may therefore be said to be divided by said lines into the following parts, to wit: the main rect- 40 angular body portion a , which is to form the back of the stand, the side flaps or wings a' and a^2 , which are to form the sides of the stand, and the narrow edge portion a^3 , which is to form a ledge along the lower portion 45 of the stand. Where the blank is cut from card-board, it will preferably be scored along the dotted lines, so as to permit it to be readily bent along such lines, while on the other hand it will be cut through along the 50 lines 4 4. In order to form a complete stand from said blank, I bend back the wings a' , as in Fig. 2, and bend forward the marginal por-

tion a^3 along line 2, so as to bring it at or about at right angles to the body portion a , as in Fig. 3, also bending back the wings a^2 , 55 so that they shall be brought against the wings a' . I then secure each wing a^2 to one of the wings a' by staples or other suitable fasteners B, it being observed that in forming the blank I find it convenient to cut 60 therein suitable openings for the legs of the staples or fasteners. By such arrangement, therefore, the portion a of the blank forms the back of the stand, the wings a' and a^2 form the sides of the stand, and the portion 65 a^3 forms a flange or forwardly-projecting ledge along the lower portion or base of the holder.

The leaves C are attached to the back of the stand by any desired number of bowed or arched staples D, which have their legs inserted 70 through the back and bent down upon the rear side thereof. The staples D are desirably shouldered at the points where their arched body portions are prolonged to form the legs, so that the legs can be inserted through the 75 back a up to said shoulders. By the foregoing arrangement of staples D for attaching the leaves to the back of the stand a book of such leaves can be opened at any point, and when so opened its two divisions will lie flat 80 against the back of the stand. The ledge a^3 protects the lower edges of the leaves and prevents any sagging thereof. Moreover, should it be desired to detach the leaves and staples 85 D from the stand, a card or picture can be placed against the back a , where it will be upheld by the ledge a^3 , and, furthermore, kept from slipping sidewise by such portions of the flaps or wings a^2 as project forward from the plane of the back a . The principal 90 feature of importance, however, involved in the part or ledge a^3 is that it holds, strengthens, and connects the wings or flaps a^2 with the back or body of the calendar-stand and holds them rigidly at right angles thereto. 95

What I claim as my invention is—

1. A stand comprising a body portion a and side flaps or wings a' a^2 , formed from a single piece, said side flaps or wings being bent at an angle to the said body portion, so that 100 one edge of each of said flaps or wings will be in position to support said stand, the plane in which said edges lie being at less than a right angle to said body portion, whereby said

body portion will stand in a tilted position, substantially as set forth.

2. A stand comprising a body portion a and two sets of side flaps or wings $a' a'$ and $a'' a''$, 5 formed from a single piece, said side flaps or wings being bent and secured together at an angle to said body portion and arranged to support said stand by one edge of each of said flaps or wings, substantially as described.
- 10 3. A stand comprising a body portion a , side flaps or wings $a' a'$, and an outwardly-extending bottom ledge or support a^3 , formed from a single piece, substantially as described.

- 15 4. A stand comprising a body portion a , having side wings or flaps $a' a'$ for supporting said stand, and an outwardly-extending

bottom ledge or support a^3 , said bottom ledge or support having side wings or flaps $a^2 a^2$ for attachment to said side wings or flaps $a' a'$, for securing said bottom ledge or support in 20 position, substantially as set forth.

5. As an improved article of manufacture, a stand having a set of leaves, staples securing said leaves to the stand, and an outwardly-extending bottom ledge or support a^3 , 25 located beneath said leaves and adapted to support the same, substantially as described.

FRED M. TURCK.
